HANDLE-LOCKING DEVICE FOR PNEUMATIC TOOLS.

1,170,779.

Specification of Letters Patent.

Patented Feb. 8, 1916.

Application filed May 24, 1915. Serial No. 29,999.

To all whom it may concern:

Be it known that I, REINHOLD A. NORLING, a citizen of the United States, and a resident of Aurora, in the county of Kane and State 5 of Illinois, have invented certain new and useful Improvements in Handle-Locking Devices for Pneumatic Tools; and I do hereby declare that the following is a full, clear, and exact description thereof, reference being had to the accompanying drawings, and to the letters of reference marked thereon, which form a part of this specification.

This invention relates to locking devices for pneumatic tools and more particularly 15 to means for locking the handle of such a tool to the body or barrel thereof. Pneumatic tools, constructed in such a manner as to make a locking device of the character described applicable, ordinarily comprise a 20 tubular member or barrel having a central bore or cylinder, within which is mounted an endwise movable member or piston actuated by air pressure, alternately admitted at either end of the bore through the medium 25 of suitable air passages communicating therewith, and valve mechanism for controlling the admission of compressed air to said passages. The movable piston is adapted by its movement within the barrel to deliver sharp blows with great rapidity upon 30 the end of a tool inserted within one end of the barrel. This tool may be one of several varieties, depending on whether the particular pneumatic tool is a hammer, riveter, chisel, or other form of tool capable 35 of performing work by a succession of rapid blows. There is ordinarily provided, at the end of the barrel opposed to the tool-holding end thereof, a handle having a cylindric 40 sleeve or socket portion, which is removably connected to the end of the barrel by means of screw threads. The operation of the tool is accompanied by a considerable degree of vibration, due to the rapidity and force with 45 which the blows are delivered, and, in the absence of means for locking the handle to the barrel, the effect of the vibration is a relative rotative movement of the parts tending to unscrew the handle from the barrel.

50 In order to prevent the handle from being unscrewed from the barrel, it is desirable to provide means for locking the members together, so that, having assembled the parts, the locking device may be adjusted, thereby 55 assuring the tight connection of said handle

and barrel. It is to such a locking device that this invention relates, and the features of construction will be readily understood from a description of a form of tool to which the locking device is applicable, and in connection with the accompanying drawings, in which—

Figure 1 is a view in elevation of a pneumatic tool to which the locking device is applied; Fig. 2 is a fragmentary view in elevation of the tool with a portion broken away to show the form of connection between the barrel and handle, and also showing the members of the locking device in section; Fig. 3 is an enlarged cross-sectional view taken on line 3—3 of Fig. 1; and Fig. 4 is an enlarged cross-sectional view taken on line 4—4 of Fig. 1.

Referring more in detail to the construction of the particular form of pneumatic tool embodying the features of the invention, the same comprises two main parts or members, namely, the barrel 10 and the handle 11. As before mentioned, in connection with tools of this character, the barrel consists of a tubular member having a central bore, within which travels a reciprocating plunger, said plunger being actuated by means of compressed air admitted to the ends of the bore or cylinder through suitably arranged air passages 12, 12 (Figs. 3 and 4), formed in the barrel 10 and extending longitudinally thereof. The admission of air to the bore is controlled by valve mechanism located at the end of the barrel 85 adjacent to the handle, said valve mechanism being arranged to direct the air alternately into the bore at the opposite ends thereof, thereby effecting the rapid reciprocatory movement of the plunger within the 90 barrel. Certain of said air passages 12, 12 constitute exhaust passages whereby the air is discharged from the barrel at the proper intervals, through the medium of the valve mechanism. Since the particular operating 100 mechanism of the tool forms no part of this invention, it is not thought necessary to illustrate or describe in detail the construction thereof, it being understood that a tool, such as a riveter or hammer, is inserted in 105 the opposite end of the barrel from the handle, the same being adapted to receive blows delivered in rapid succession by the plunger.

The handle 11 comprises a grip or handle 110

portion 13 arranged transversely to the barrel in the usual manner and adapted to be grasped by the operator in manipulating the tool. The grip 13 is connected by means 5 of a curved neck portion to a cylindric socket portion 14 of the handle 11, said socket having an open end and adapted to receive the adjacent end of the barrel, said parts having screw-threaded connection, as hereininafter more fully described. At the lower extremity of the handle is provided an air inlet member 15 adapted to be connected to a compressed air supply, by means of a suitable hose and hose connection. The air inlet member 15 communicates with an air passage formed within the handle and adapted to conduct the air to said valve mechanism located within the adjacent end of the barrel 10 and surrounded, in part, by the socket portion 14 of the handle. A valve is also provided within the handle 13, the same comprising a control lever 16 projecting outwardly from the upper end of the grip portion 13, and adapted to be manipulated by 20 the thumb of the operator in starting and stopping the tool.

The extremity of the barrel adjacent to the handle is provided with a screw-threaded portion 17 (Fig. 2) adapted to engage screw threads formed upon the inner surface of the socket 14 of the handle, said screw threads of the socket being preferably located a short distance inwardly from the margin of the socket, so that when the handle is screwed tightly onto the end of the barrel said margin of the socket will project a short distance beyond the threaded portion 17 of the barrel. Spaced inwardly from said screw-threaded portion of the barrel and intermediate of the ends thereof, is formed an integral collar 18 adapted to form a shoulder spaced from the margin or edge of the socket portion of the handle, the portion of the barrel intermediate the shoulder 40 formed by said collar and the threaded portion 17 being preferably of uniform diameter.

Between the shoulder 18 and the margin of the socket portion 14 of the handle, is 50 located the locking device embodying my invention, and which may be described as follows: Surrounding the barrel, intermediate the shoulder 18 and the end of the socket, is a split ring 19 having the nature 55 of a peripherally resilient or expansible ring, said ring being slightly greater in its internal diameter than the external diameter of that portion of the barrel surrounded by it. The ring is adapted to be contracted or 60 decreased in diameter by having its ends drawn together, and, therefore, its diameter is variable, although it is preferred to have the diameter of the ring slightly greater than the diameter of the barrel, 65 even when in contracted condition. At the

ends of the split ring, adjacent to the point where the same is split or cut, are provided integral lugs 20, 21 extending transversely to the rings and in opposite directions. One of the lugs 20 engages a notch 22 formed in 70 the margin of the socket portion of the handle, and the other lug 21 engages a similar notch 23 formed in the adjacent margin of a collar 24 rotatively mounted upon the barrel intermediate the split ring 19 and 75 the shoulder 18. The collar 24 is adapted to be revolved about the barrel and to be secured in one of several positions, the following means being preferably employed to accomplish this object: Arranged circumferentially about the collar are provided a series of equally spaced apertures 25 located midway of the margins of the same. These apertures are adapted to register with a series of holes or cylindric depressions 26 80 formed in the barrel, said holes being spaced at equal distances apart about the circumference of said barrel and located in the plane of the apertures 25 of the collar 24. To secure the collar to the barrel and to prevent rotation of the former about said barrel, a cylindric plug or locking member 27 (Fig. 3) is employed, the same being preferably provided with a beveled or tapered surface 27^a at one end thereof. The plug 95 is adapted to be inserted through an aperture 25 of the collar and into a hole 26 of the barrel, when the collar is rotated to a position in which one of the apertures of the collar and a hole of the barrel are brought 100 into registering relation, thereby locking the collar from rotation upon the barrel. It is preferable to provide a greater number of holes in the barrel than there are apertures in the collar, thereby permitting a greater degree of adjustment of the collar, in that a less angle of rotation of the collar is required to bring an aperture thereof into registering relation with a hole of the barrel. Furthermore, the formation of the apertures 105 is preferably such as to afford a more secure locking or retention of the plug in locking position, namely, by tapering a portion of the walls of the apertures in a direction slightly inclined to a radial line representing the normal axis of the aperture, thereby increasing the circumferential dimension of each aperture. As shown in Fig. 3, the effect of tapering the apertures is to provide at one side of each aperture an edged shoulder adjacent to the inner surface of the collar and at the opposite side a similar shoulder adjacent to the outer surface of the collar. Thus, when the plug is inserted in locking position, the shoulder adjacent to the outer surface of the aperture will engage said tapered surface 27^a at the outer extremity of the plug, it being understood at this time that, when the collar is 120 in locked position, there is a force exerted 125 130

on it by the split ring tending to rotate the collar in a counter-clockwise direction, as will be further described. Furthermore, the shoulder at the opposite side of the aperture 5 engages the plug at a point below the tapered shoulder of said plug, and hence, by reasons of the force exerted by the collar on said plug at different points along its axis, the tendency is to turn the plug about a 10 transverse axis, and consequently effecting the jamming of the plug within the holes of the barrel, to the end that the plug is more securely held within said hole.

Referring now to the function of the locking device, the same may be understood from the following: Let it be assumed that the threads upon the handle and the barrel are arranged right-handed, or, in other words, that the handle is rotated from right 20 to left in screwing the same upon the barrel and, further, assuming that said handle and barrel are disconnected, and it is desired to assemble the parts, the plug 27 being removed from the collar and barrel, thereby 25 permitting said collar and the split ring to rotate freely upon the barrel. The handle is first screwed onto the barrel in the usual manner until the notch 22 of the socket portion of the handle engages the corresponding 30 lug 20 of the split ring 19. Further rotation of the handle in the act of screwing the handle tightly upon the barrel carries with it the split ring and collar, which, as before stated, are free to rotate. When the handle 5 is screwed on as far as possible, that is, when further rotation of the handle is impossible, the collar is now grasped by the hand and further rotated in the same direction as that of the handle in being screwed 0 upon the barrel. The barrel being stationary, the rotation of the collar produces a contraction of the split ring accompanied by a reduction of the diameter and a bringing together of its ends. When a point is 5 reached where the ring is tightly contracted, and the collar can no longer be rotated, the plug is inserted into an aperture and hole of the collar and the barrel, which are found to be in registering position, as shown in 0 Fig. 3. When the plug is finally inserted in locking position, and the collar is released, the tendency of the split ring to expand exerts a force upon the collar tending to rotate it in the opposite direction, namely, 5 counter-clockwise, with reference to Fig. 3. By reason of this force, the plug becomes securely locked in position by the action thereon of the shoulders formed by tapering said apertures as hereinbefore described. 10 The collar being locked from rotation and the split ring wound up, so to speak, the latter exerts a constant tension upon the handle tending to rotate the same in a direction to screw the same more tightly upon the barrel. In this manner, therefore, the

collar and split ring act to retain the handle firmly upon the barrel, thereby preventing the said members from becoming unscrewed or loosened by reason of the vibration of the tool or from other causes. It is apparent 70 that the device can be easily unlocked by rotating the collar in a clockwise direction (Fig. 3) a sufficient amount to permit the plug to be removed. Thus the collar and ring are free to rotate, and the handle can 75 be removed in the usual manner.

A locking device embodying the features herein described is simple in structure and admits of ease in operation, having no delicate parts that are easily broken by the 80 rough usage to which the tool is subjected.

Having described in detail the construction of a device embodying the features of my invention, what I claim as my invention is—

1. A pneumatic tool, comprising a handle member and a body member adapted to be connected together at adjacent ends by the relative rotation of said members in one direction, and means for locking said members 90 from rotation in the opposite direction, comprising a circumferentially adjustable member mounted on one of said members intermediate its ends and adapted to be locked thereto in one of several adjusted positions, 95 and a resilient tension member interposed between and connected with said adjustable member and with the end of the other of said members, said adjustable member being adapted to vary the tension of said resilient 100 member.

2. A pneumatic tool, comprising a handle member and a body member having screw-threaded end portions adapted to be screwed tightly together, and means for locking said 105 members together, comprising a resilient member adapted to be connected at one of its ends to the end of one of said members, and a circumferentially adjustable member mounted on the other of said members 110 intermediate of its ends and connected with the opposite end of said resilient member.

3. A pneumatic tool, comprising a handle member, a barrel member adapted to have threaded engagement with said handle member, one of said members being provided with a threaded socket adapted to receive a threaded end of the other member, a circumferentially adjustable member mounted on one of said members intermediate its ends 115 and adjacent to the socket of the other of said members, and a resilient member interposed between and connected with said adjustable member and the margin of said socket.

4. A pneumatic tool, comprising a handle provided with a socket, a barrel having screw-threaded connection with said socket, a peripherally resilient member surrounding said barrel adjacent to the said socket 130

and connected at one of its ends to said handle member, and a rotative collar mounted on said barrel and connected with the opposite end of said resilient member, said 5 collar being adapted to be rotated to vary the tension of said resilient member and to be locked to said barrel in one of several adjusted positions.

5. A pneumatic tool, comprising a barrel, 10 a handle provided with a socket adapted to have screw-threaded engagement with one end of said barrel, a split tension ring surrounding said barrel and connected at one end to said handle, a tension adjusting member connected to the other end of said 15 ring and interposed between said ring and said barrel, and means for locking said adjustable member to said barrel.

6. In a device of the character described, 20 the combination of a barrel, a handle provided with a threaded socket adapted to receive the threaded end of said barrel, a peripherally expansible split ring surrounding said barrel and provided at its ends with 25 transversely extending lugs, said socket of the handle being provided with a marginal notch adapted to receive one of said lugs, and an adjustable member mounted on said barrel and adapted to engage the other of 30 said lugs of the ring, said adjustable member being adapted to vary the tension of said ring and to be locked to said barrel in one of several adjusted positions.

7. In a device of the character described, 35 the combination of a barrel, a handle provided with a socket adapted to have screw-threaded engagement with one end of said barrel, a split tension ring surrounding said barrel and connected at one end to said handle, a collar rotatively mounted on said 40 barrel and connected with the other end of said ring, said collar being provided with an aperture adapted to register with a hole formed in said barrel, and a removable plug 45 adapted to be inserted in said aperture and hole to lock said collar from rotation on said barrel.

8. In a device of the character described, 50 the combination of a barrel, a handle provided with a threaded socket adapted to receive the threaded end of said barrel, a peripherally expansible split ring surrounding said barrel and provided at its ends with transversely extending lugs; said sockets of 55 the handle being provided with a marginal

notch adapted to receive one of said lugs, a collar rotatively mounted on said barrel adjacent to said ring and provided with a marginal notch adapted to receive the other of said lugs of the ring, and means 60 for locking said collar to said barrel in one of several adjusted positions.

9. In a device of the character described, the combination of a barrel, a handle provided with a threaded socket adapted to receive a threaded end of said barrel, a collar rotatively mounted on said barrel and provided with a series of circumferentially arranged apertures, said barrel being provided with a series of circumferentially arranged 70 holes adapted to register with said apertures of said collar, a peripherally expansible member surrounding said barrel, interposed between and connected with said handle and collar, and adapted to be contracted by 75 the rotation of said collar, and means for locking said collar to said barrel in one of several positions, comprising a plug adapted to be inserted in a registering aperture of said collar and a hole of said barrel. 80

10. In a device of the character described, the combination of a barrel, a handle provided with a threaded socket adapted to receive a threaded end of said barrel, said barrel being provided with a shoulder adjacent to the threaded end thereof and a series of circumferentially arranged holes adjacent to said shoulder, a collar rotatively mounted on said barrel intermediate said shoulder and the threaded extremity thereof 90 and having a series of circumferentially arranged apertures adapted to register with said holes of the barrel, a peripherally expansible member surrounding said barrel and connected with said handle and collar 95 and adapted to be contracted by the rotation of said collar, and means for locking said collar to said barrel in one of several positions, comprising a plug adapted to be inserted in a registering aperture of said 100 collar and a hole of said barrel.

In testimony that I, claim the foregoing as my invention I affix my signature in the presence of two witnesses, this 20th day of May, A. D. 1915.

REINHOLD A. NORLING.
